UNITED STATES PATENT OFFICE

131,895

DESIGN FOR A SUCTION PUMP UNIT

Edmond O. Pratt, Los Angeles County, Calif.

Application September 26, 1941, Serial No. 103,526

Term of patent 7 years

To all whom it may concern:

Be it known that I, Edmond O. Pratt, a citizen of the United States, residing in the county of Los Angeles and State of California, have invented a new, original, and ornamental Design for a Suction Pump Unit, of which the following is a specification, reference being had to the accompanying drawing, forming part thereof.

Fig. 1 is an end elevational view of a suction pump unit showing my new design; Fig. 2 is a

top plan view thereof with the legs omitted; and Fig. 3 is a front elevational view on a slightly enlarged scale with the legs broken away for convenience of illustration.

The dominant features of the design reside in the portions shown in full lines.

I claim:

The ornamental design for a suction pump unit, as shown and described.

EDMOND O. PRATT.
